CLAIM

The ornamental design for a set of wireless earphones and charging case, as shown and described.

DESCRIPTION

FIG. 1 is a perspective view of wireless earphones of a set of wireless earphones and charging case, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the charging case of the set of wireless earphones and charging case, shown separately for ease of illustration and in an open configuration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the set of wireless earphones and charging case where the wireless earphones are received in the charging case; and,

FIG. 18 is a perspective view of the charging case of the set of wireless earphones and charging case, shown separately for ease of illustration and in a closed configuration.

The broken lines in the drawings depict portions of the set of wireless earphones and charging case that form no part of the claimed design.
